UNITED STATES PATENT OFFICE.

HARRY I. GLASER, OF DORCHESTER, MASSACHUSETTS, ASSIGNOR TO GLASER BROS., OF BOSTON, MASSACHUSETTS, A CORPORATION OF MASSACHUSETTS.

DESIGN FOR A FINGER RING.

Application filed May 22, 1925. Serial No. 13,539. Term of patent 7 years.

To all whom it may concern:

Be it known that I, HARRY I. GLASER, a citizen of the United States, residing at Dorchester, in the county of Suffolk and State of Massachusetts, have invented a new, original, and ornamental Design for Finger Rings, of which the following is a specification, reference being had to the accompanying drawing, forming part thereof.

Of the drawings, Figure 1 represents a side perspective view of a finger ring showing my new design, and

Figure 2 represents an edge perspective view.

I claim:

The ornamental design for a finger ring as shown.

HARRY I. GLASER.
